CLAIM

The ornamental design for a rack and label, as shown and described.

DESCRIPTION

FIG. 1 is perspective view of a rack and label showing our new and ornamental design;

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The broken lines shown in FIGS. 1, 6 and 7 illustrate portions of the rack and label that form no part of the
